UNITED STATES PATENT OFFICE.

CHARLES F. BASSETT, OF ALLEGHENY, PENNSYLVANIA.

DESIGN FOR A WINDOW-SHADE FIXTURE.

SPECIFICATION forming part of Design No. 34,714, dated July 2, 1901.

Application filed April 26, 1901. Serial No. 57,636. Term of patent 14 years.

To all whom it may concern:

Be it known that I, CHARLES F. BASSETT, a citizen of the United States of America, residing at Allegheny, in the county of Allegheny and State of Pennsylvania, have invented and produced a certain new and original Design for Window-Shade Fixtures, of which the following is a specification, reference being had therein to the accompanying drawing.

This invention relates to new and original designs in shade-fixtures, and has for its object to produce a design of this character that will be extremely pleasing to the eye and decidedly ornamental in its appearance.

The invention consists in the novel form, configuration, and contour of the design, as illustrated in the drawing, which shows a perspective view of the same.

In the drawing the reference-numeral 1 indicates a circular base portion, which is slightly convexed on each face, having formed centrally therein an opening 2, said opening

2 having scalloped edges surrounding the same, which are indicated by the reference-numeral 3. Extending radially around said scalloped edges are S-shaped configurations 4, forming the novel design, as shown. The reference-numeral 5 indicates a shank attached to said circular base portion 1, this shank being also cylindrical in form and carrying an enlarged offset 6. The reference-numeral 7 represents a tapering screw attached to said enlarged portion 6.

Having fully described my invention, what I claim as new, and desire to secure by Letters Patent, is—

The design for a window-shade fixture, substantially as herein shown and described.

In testimony whereof I affix my signature in the presence of two witnesses.

CHARLES F. BASSETT.
